UNITED STATES PATENT OFFICE.

SIDNEY C. VESSY, OF CLEVELAND, OHIO, ASSIGNOR TO THE STAR SEAL & CLOSURE COMPANY, OF CLEVELAND, OHIO, A CORPORATION OF OHIO.

METHOD AND APPARATUS FOR SEALING CONTAINERS.

Application filed October 28, 1918. Serial No. 259,975.

To all whom it may concern:

Be it known that I, SIDNEY C. VESSY, a citizen of the United States, residing in Cleveland, in the county of Cuyahoga, State of Ohio, have invented certain new and useful Improvements in Methods and Apparatus for Sealing Containers, of which the following is a specification.

This invention relates broadly to the package closing art and to metal spinning devices and more especially to devices for sealing glass containers and the like with metal caps.

The principal object of the present invention is the method and apparatus for spinning the bead of a suitable metal cap over a resilient gasket and against the substantially incompressible side wall of a glass container and the like.

20 A more specific object of the present invention is the method and apparatus for sealing a metal cap or the like upon a suitable glass container by gradually deforming a metal bead and compressing the same over a suitable gasket and against the substantially incompressible side wall of a glass container or the like in such manner that the sealing forces are directed toward a common sealing zone.

25 Still more specifically the present invention comprises the sealing of a metal cap or the like over a suitable glass container or the like by deforming a bead in the skirt of the cap over a compressible gasket in such manner that the deforming forces are applied locally and gradually from one edge of the bead to the other edge, whereby the gasket is compressed under angularly disposed forces and toward a common sealing zone.

30 A still further and equally important object of the present invention is the method and apparatus for sealing suitable metal caps over glass jars or the like by gradually spinning a bead in the skirt of the cap over a compressible gasket by applying the spinning forces to the upper portion of the head in an inward and downward direction and gradually changing the direction 45 of the spinning forces in such manner that the spinning action is completed by spinning forces directed inwardly and upwardly.

35 Another object of the present invention is the method and apparatus of sealing a suitable metal cap upon a glass container or the

like by providing a bead in the skirt of the cap, placing a compressible gasket within said bead, then deforming said bead radially by locally applying spinning forces thereto in such manner that said bead is deformed 60 to compress the gasket tightly against the side wall of the container.

The present invention possesses many other advantageous features, some of which, with the foregoing, will be set forth more 65 at length in the following description, wherein will be outlined in full that form of the invention which I have selected for illustration in the drawings accompanying 70 and forming a part of the present specification.

In the drawings I have shown only one specific form of my generic invention, but it is to be understood that I do not limit myself to such form, because my invention 75 may be embodied in a multiplicity of forms, each being a species of my invention. It is also to be understood that by the claims succeeding the description of my invention I desire to cover the invention in whatsoever 80 form it may be embodied or practiced.

Referring now to the drawings, wherein like reference characters refer to like parts throughout the several figures thereof:

Figure 1 is a detail view of one form of 85 spinning mechanism for carrying out the present invention and is a section on line A—B of Figure 3.

Figure 2 is a sectional view taken on line C—C of Figure 1.

Figure 3 is a sectional view taken on line A—B of Figure 1.

Figure 4 is a view illustrating one form 90 of a complete machine for carrying out my invention.

Figure 5 is a diagrammatic view illustrating the action at the beginning of the spinning operation.

Figure 6 is a view similar to Figure 5 95 illustrating a spinning roll in contact at 100 two points on the bead.

Figure 7 is a detail view illustrating a further step in the spinning operation.

Figure 8 is a detail view illustrating a 105 complete spinning operation, and

Figure 9 is a view illustrating the completed package.

Heretofore in the art of sealing metal caps upon glass containers and the like it has been customary to deform the sealing bead 110

on the skirt of the cap by means of chucks or dies wherein substantially the entire bead is simultaneously deformed to compress the gasket against the side wall of the container. 5 This sealing operation by means of chucks or dies requires a considerable compressive force, often as much as several thousand pounds pressure. This force is so exerted by the chucks or dies that unless the glass 10 and the cap are accurately sized to the chucks or dies, there is liability of breakage, or an improper seal. Where chucks or dies are used, as is common in the art, there is liability of the force causing the 15 chucks or dies to wear in such manner that there is a tendency to deform one side of the bead differently from the deformation of the bead on the diametrically opposite side of the container. This fact also tends 20 to produce unsatisfactory seals where chucks or dies are used. Furthermore, where chucks or dies are used in substantially all cases the deforming of the bead comprises a compression of the bead substantially 25 parallel to the side wall of the container, which compresses the gasket vertically and causes a squeezing of the gasket radially as an incident to the vertical compression. It is to be noted that under these circumstances 30 the major forces are exerted in a vertical direction rather than in a radial direction where the compression is most effective to form the seal.

The present invention overcomes the difficulties encountered in the known commercial art of sealing, as above specified, by sealing the cap on the glass container or the like by spinning the bead of the cap inwardly in a radial direction in such manner that the gasket in the bead of the cap 35 is gradually constricted and deformed by spinning pressure applied progressively to various parts of the bead in such manner as to tightly compress the gasket between the deformed bead and the side wall of the container, thereby forming a hermetic seal.

One form of apparatus for carrying out my invention may comprise a container table or support 1 which is adapted to lift 50 a suitable container 2 with a suitable metal cap 4 or the like thereon into contact with a yielding head 5 which is carried on a shaft 6 that extends through a head frame 7 that carries a bracket 8 which is provided with a stub screw 9 that enters a slot 10 in the shaft and permits a longitudinal movement of the shaft at the same time prevent rotation thereof. A collar 11 may be provided to adjustably limit the movement of the shaft in a downward direction. 55 A spinner head 12 is mounted to rotate over the yielding pressure head 5 and is seated upon a bearing ring 14 of fibre or other suitable antifriction bearing material. This 60 spinner head carries pivoted levers 15 on

which are mounted studs 16 that carry spinning rolls 17 having grooves 18 in their periphery which are adapted to deform the bead on the cap as will be explained later. The upper ends of the roller carrying arms 70 15 extend through openings in pressure plugs 19 which are mounted on a spinner frame 20. These pressure plugs 19 are 75 slidable in the openings in the spinner frame, in which openings are provided adjustment nuts 21 that bear upon coiled springs 22 which rest against shoulders 24 on the plugs. The upper ends of the plugs carry lock 80 nuts 25 which are adapted to be adjusted to control the inner limit of operation of the spinning rollers 17. The spinning head 12 is 85 slidable on the spinning frame 20 but is prevented from rotation thereon by means of a key 26 which extends partly into the spinning frame and partly into the spinning head. A coiled spring 27 between the spinning frame and the spinning head normally 90 maintains the spinning head bearing against the fibre washer bearing ring 14. The spinning frame is bolted by means of stub bolts 28 to a flange 29 on a hollow shaft 30 that surrounds the pressure head shaft 6. The hollow shaft 30 is provided with a shoulder 31 that likewise bears on an antifriction or bearing washer 32 carried 95 adjacent the head of the frame.

A drive pulley 34 is mounted on the hollow shaft 30 and is adapted to rotate the shaft and the spinning mechanism. Referring to Figure 4 the spinning mechanism is shown as being mounted upon a pedestal 35 in which is pivoted a foot lever 36 that is normally maintained at its upper limit of movement by means of a coiled spring 37 anchored at one end of the lever and at the other end of the pedestal. An upwardly extending link 38 connects the pedestal with the lifter lever 39 which is pivoted on the pedestal and extends through a lifter bar which carries an anti-friction roll 40 that bears on the lifter lever. The lifter bar is formed of two pieces 41 and 42 that are connected together with a clamp coupling 44 in such manner that the length of the lifter bar may be increased or decreased to raise or lower the zone of movement of the receptacle table 1 mounted on the upper section of the lifter bar. The lifter bar is guided through a sleeve 45 which is also mounted on the pedestal 35. Preferably the spinning mechanism is inclosed by a shield 46 which comprises the connection between the pedestal and the head frame. 115

It will be noted that when pressure is brought to bear on the foot lever 36 the connected parts raise the package table 1 and bring the top of the cap 4 into contact with the pressure head 7 at which time the bead on the cap is opposite the grooves 18 in the spinner rollers 17. Further upward 120 125 130

movement of the pedestal lifts the package still higher and lifts the pressure head which compresses the coiled spring 27 between the spinner head 12 and the spinner frame 20 whereby the spinner roll levers 15 tend to raise the lever pressure plugs 49 and compress the pressure plug springs 22. When the machine is in operation the power wheel is belted to a continuous rotating source of power so that the spinning head and the spinning frame are revolving at the time when the spinner rolls engage the flange on the cap. As pressure is brought to bear on these rolls the bead is gradually spun in and the seal completed.

Referring more particularly to Figures 5 to 8 inclusive and Figure 1, it will be noted that in the preferred form the method of sealing comprising my invention is carried out by utilizing a metal cap having a substantially right angular bead 47 in the skirt of the cap which encloses a gasket of rubber composition or suitable material 48, which gasket comprises a ring substantially rectangular in cross-section. The groove 18 in the spinning roll 17 is curved in such manner as to distort the said bead when the spinning operation is completed. It will be remembered that the spinning roll has three paths of movement, one being the path around the receptacle, the other being the rotation of the spinning roll upon its pivot 16 and the other being the swinging movement of the spinning roll around the pivot 35 of the lever 15. The first two paths of movement have to do with the spinning operation, whereas the third path of movement controls the direction at which the spinning roll approaches the bead to be spun. Referring to Figure 5 it will be noted that the spinning roll contacts first with the upper corner of the bead to compress the gasket inwardly and downwardly as indicated by the arrow 49. In Figure 6 it is to be noted that the spinning operation has progressed by further distorting the upper portion of the bead and by the spinning roll contacting with the lower edge of the bead whereby converging compression forces, indicated by arrows 49 and 50, are set up in the gasket. In Figure 7 the spinning operation has progressed further and substantially the entire bead is subjected to the spinning action which further increases the converging compression forces. In Figure 8 the spinning is completed and in this figure it is to be noted that the compression forces, indicated by arrows 50, are strongest in the lower portion of the bead at this time when the spinning action is completed.

By this gradual distortion of the bead and the gasket it will be seen that the compression forces are directed in such manner as to cause a very compact and tight seal 65 between the side wall of the container and

the skirt of the cap, due to the converging lines of forces imposed upon the gasket. The cross section of the gasket and the shape of the groove in the spinning rolls may be varied without departing from my invention. The preferred form of my invention may be carried out by such constructions as comprise variations in cross-sectional shape between the bead and the roller groove so that a substantial distortion of the gasket occurs when the seal is completely spun.

It is also preferable that the package and cap be retained stationary and that the spinning head and spinning rollers be revolved around the cap and container to effect the spinning operation. The reason for this is that where the package is rotated there is a tendency, due to centrifugal forces, to throw outward the contents of the container. There is a liability of the liquids in the container being thrown out under the cap prior to the completing of the seal where the container is rotated. It is obvious from the construction shown in the drawings, that the pressure head and the package table being stationary, the package and the cap will also be held stationary during the spinning operation.

Having described my invention what I claim is:

1. The method of forming hermetic seals on glass containers and the like, which method comprises providing a container having a peripheral wall adjacent the mouth thereof; providing a metal cap with an angular bead in the skirt thereof; providing a gasket within said bead, then placing said cap in position over the mouth of said container; and then changing the angular character of said bead into a substantially smooth curved form in cross-section by spinning inward the angularly disposed portions of said bead whereby the gasket is compressed between the skirt of the cap and the side wall of the container.

2. The method of forming hermetic seals on glass containers and the like, which method comprises providing a container having a substantially incompressible side wall adjacent the mouth thereof; placing a metallic cap, with a substantially rectangular bead in the skirt thereof, in position to cover the mouth of the said container and with the skirt extending over the side wall of the container; providing gasket material between the bead and the side wall of the container; and then spinning the upper portion of said bead inwardly and lower portion of the bead upwardly to compress said gasket against the side wall of the container.

3. The method of hermetically sealing glass containers and the like which method comprises providing a ductile constraining

member to encompass the peripheral wall of a vessel; placing between the constraining member and said wall a ring of gasket material having a substantially rectangular cross section; and spinning the constraining member inwardly to compress the gasket and change the angular relation of the exterior sides into a curve whereby converging compressive forces are exerted against the gasket material to compress the same tightly against the side wall of the container.

4. The method of sealing glass containers and the like which method comprises providing a metal cap with a bead in the skirt of the cap; placing a ring of gasket material of substantially rectangular cross-section within the said bead and between the skirt of the cap and side wall of the container; placing the cap over the mouth of the container to be sealed; and then deforming the bead by spinning the upper outer portion inward and downward and the lower portion inward and upward to reduce the size of the bead and set up compression forces in the gasket to compress the same tightly against the side wall of the container.

5. The method of sealing glass containers and the like which method comprises providing a suitable metal cap having a bead formed in the side wall thereof; placing a ring of gasket material within said bead, the said ring of gasket material being substantially rectangular in cross section; then holding the package and the cap stationary; and then subjecting the bead to the spinning action of a smooth grooved roller which is swung in an arc toward the side wall of the container whereby the upper portion of the bead is first subjected to the spinning action and the lower portion of the bead is last subjected to the spinning action.

6. The method of hermetically sealing glass containers and the like, which comprises providing a suitable metal cap having a substantially right angular bead in the skirt thereof; placing a ring of gasket material within said bead; then placing said cap in position over the mouth of a suitable container; then holding the container and the cap stationary; then subjecting the bead and the gasket to spinning forces moving around the said bead on an axis of revolution coincident with the axis of the mouth of the container; and then causing the spinning forces to be effective from one edge of the bead to the other edge of the bead whereby the spinning forces are convergent to decrease the diameter of the bead and tightly compress the basket against the side wall of the container.

7. In a metal spinning machine, the combination of a frame adapted to rotate on a substantially vertical axis, means for stationarily supporting a package with its closure coaxial with the frame; rotatable

spinning rollers carried by said frame for movement about said axis, and means effective to move said rollers toward said axis and to incline their axes from and toward said axis.

8. In a machine of the class described, the combination of a rotatable spinning frame, means for supporting a container with its closure on an axis with said frame, a spinning roller rotatably carried by said spinning frame, and means operable to move said roller toward and from the axis of the spinning frame and to rock it across a plane perpendicular to said axis.

9. In a machine of the class described, the combination of a spinning frame mounted for rotation on a vertical axis, rollers carried by said frame and movable about said axis, and mountings for said rollers operable to vary the inclination of their axes both ways from the vertical and means for operating said mountings.

10. In a machine of the class described, the combination of a spinning frame mounted for rotation on a substantially vertical axis, rollers carried by said frame and movable about said axis, said rollers having peripheral spinning faces, and means for tilting the rollers to render their spinning faces effective in synclinal and anticlinal relationships.

11. In a machine of the class described, the combination of a rotatable spinning frame, a spinning roller carrier by said frame, and movable about the axis of the frame, said roller having a transversely curved peripheral spinning face, a mounting for said roller, and means operable to move the roller laterally and to rock it to render its spinning face effective first downwardly and then upwardly.

12. In a machine of the class described, in combination, a spinning head mounted for rotary movement, a plurality of roller mountings spaced apart upon said head, rollers carried on said mountings and having laterally directed spinning faces, and means operably effective upon the roller mountings to move the rollers inwardly toward the axis of the spinning head and to rock the rollers to render their spinning faces effective first downwardly and then upwardly.

13. A machine for hermetically sealing glass containers or the like by spinning a bead containing a gasket against the side wall of the container; said machine comprising a spinning head, a plurality of rollers carried by said spinning head, a groove in each of said spinning rollers, and means to cause said rollers to be effective during a portion of the spinning operation to spin the bead inwardly and during another portion of the spinning operation to spin the edge of the bead upwardly.

14. A machine for hermetically sealing glass containers or the like by spinning a bead containing a gasket against the side wall of the container; said machine comprising a spinning head, a plurality of rollers carried by said spinning head, a groove in each of said spinning rollers, and means to swing said rollers in such manner that said rollers are effective during a portion 10 of the spinning operation to spin the bead inwardly and during another portion of the spinning operation to spin the edge of the bead upwardly.
15. In a machine of the character specified 15 the combination of a spinning frame comprising a head adapted to rest on a suitable cap during the spinning operation, and spinning rollers having a swinging movement
- whereby a suitable bead on said cap is first spun inwardly and then the lower edge of the bead is spun upwardly and inwardly to compress a suitable gasket against the side wall of the container.
16. In a machine of the character specified 20 the combination of a spinning head, a spinning frame, a stationary head adapted to rest on a suitable cap during the spinning operation, spinning rollers, and means to impart an orbital movement to said rollers whereby a suitable bead on said cap is first 25 spun inwardly and then the lower edge of the bead is spun upwardly and inwardly to compress a suitable gasket against the side wall of the container.

SIDNEY C. VESSY.
